UNITED STATES PATENT OFFICE.

WALTER A. McGRAW, OF MOUNT PLEASANT, TEXAS.

STRAW-RACK FOR THRESHING-MACHINES.

1,200,002.

Specification of Letters Patent.

Patented Oct. 3, 1916.

Application filed January 31, 1916. Serial No. 75,331.

To all whom it may concern:

Be it known that I, WALTER A. McGRAW, a citizen of the United States, residing at Mount Pleasant, in the county of Titus and State of Texas, have invented certain new and useful Improvements in Straw-Racks for Threshing-Machines, of which the following is a specification.

This invention relates to new and useful improvements in straw racks for threshing machines.

The object of the invention is to provide a rack having a transversely corrugated bottom or one having its bottom formed of substantially A-shaped sections, each successive section being higher than its predecessor; and the upwardly inclined surfaces having perforations or openings and means for retarding the progress of the straw over the rack whereby the grain is caused to drop through the openings, while the downwardly inclined surfaces have openings permitting the passage of the grain.

Another object is to provide in combination with the openings and retarding means, a plurality of transverse serrated or notched bars which act to spread the straw so that the chaff will be more readily removed and the grain be given full opportunity to fall through the openings, said bars also acting to retain the grain on inclined surfaces.

A further object is to provide a rack which will separate the grain, straw and chaff to the fullest extent, whereby very little if any of the grain will be lost over the end of the rack and the straw will be thinly spread over the bottom of the rack and not congested.

A still further object of the invention is to provide a rack of the character described that will be strong, durable, efficient and simple and comparatively inexpensive to construct, also one in which the several parts will not be likely to get out of working order.

With the above and other objects in view, the invention has relation to certain novel features of construction and operation, an example of which is described in the following specification and illustrated in the accompanying drawings, wherein:

Figure 1 is a side elevation of the improved rack, Fig. 2 is a partial plan view, and Fig. 3 is a detail in perspective of one of the sections of the bottom.

In the drawings the numeral 1 designates

the frame of the rack which may be of the usual construction and attached to the usual oscillating means. The invention resides primarily in the bottom of the rack which is formed of sheet metal and composed of a plurality of substantially A-shaped sections 2 extending transversely thereof, each successive section having its ridge at a higher elevation than its predecessor. The sections each have an upwardly inclined surface or side 3 and a downwardly inclined surface or side 4. At the discharge end of the rack an upwardly inclined tail section 5 extends from the last section 2.

The rack is reciprocated or oscillated in the usual manner whereby the straw is stepped up the sides 3 and down the sides 4 to the section 5 from which it is delivered. During this transit all of the grain and chaff are removed. In the racks now commonly in use much grain is lost at the discharge end of the rack and the rack herein set forth will reduce this loss to a minimum.

The sides 3 of the section tongues or lugs 6 are provided as by striking up the same from the metal of the bottom. These tongues are preferably arranged in rows transversely of the sections so that their faces are at right angles to the line of travel of the straw. Openings 7 are provided when the tongues are struck up, but these openings might be otherwise formed. Serrated or notched bars 8 are fastened transversely on the sides 3 and 4 in spaced order and the tongues and openings are disposed between these bars. In the sides 4 openings 9 similar to the openings 7 are disposed between the bars; however the tongues 10 from these openings are bent downward. The section 5 also has the bars 8, openings 7 and tongues 6.

The bars 8 owing to their serrated construction cause the straw to spread over the entire surface of the rack and prevent congestion either transversely or longitudinally of the rack. By thus spreading or thinning the straw the chaff is more readily blown out and the grain is given a better opportunity to separate itself from the straw. As the straw is stepped up the sides 3 the tongues 6 act to retard its progress so that the grain is freed therefrom and may fall through the openings 7 to the riddle (not shown) below. It is apparent that this retarding of the straw together with the oscillation of the rack will very

effectually separate the grain which will be caught by the bars 8 and prevented from rolling down the sides of the sections.

The straw is carried over the ridges of 5 the sections and passes down the sides 4 of the same, the grain being caught by the bars and dropping through the openings 9. There being no tongues in the path of the straw on the sides 4 the straw is not re- 10 tarded, but is retained in its spread condition by the bars 8 so that grain may be freed. When the straw reaches the section 5 very little if any grain will remain, however this section is made sufficiently long 15 and provided with enough bars 8 and tongues 6 to make for a very efficient removal of the last grains which are conveyed back by the usual pan 11.

It is pointed out that the tongues 6 will 20 have a tendency to hold the grain and chaff back as the straw progresses and that considerable of the chaff will pass through the openings 7 and 9 with the grain. It is also evident that the capacity of the rack is in- 25 creased and the separation more quickly performed.

The invention is presented as including 30 all such modifications and changes as properly come within the scope of the appended claims.

What I claim, is:

1. A straw rack for threshing machines comprising a transversely corrugated bottom the corrugations of which are provided 35 with openings on both sides for the passage of grain, the upwardly inclined sides of the

corrugations having projections for retard-
ing the progress of the straw thereover, and
transverse serrated bars disposed on the
bottom substantially parallel with the 40
ridges of the corrugations.

2. A straw rack for threshing machines comprising a sheet metal bottom trans-
versely corrugated whereby upwardly and
downwardly inclined sides are provided, 45
tongues struck up from the upwardly in-
clined sides adjacent grain openings, open-
ings in the downwardly inclined sides, said
bottom having a comparatively long tail 50
section also provided with the tongues and
openings, and serrated bars disposed in
spaced order transversely of the bottom on
the inclined sides and also on the tail section.

3. A straw rack for threshing machines 55
which includes a transversely corrugated
bottom the corrugations of which are pro-
vided with openings for the passage of
grain therethrough, means for retarding the
progress of the straw along the rack, and 60
straw spreading elements disposed on the
upwardly inclined sides of the corrugations
of the bottom longitudinally of said corru-
gations and transversely of the bottom, the
openings of the bottom being located be- 65
tween the straw spreading elements whereby
the grain caught between the elements is
delivered to the openings.

In testimony whereof I affix my signature.

WALTER A. McGRAW.
